US00D362823S

United States Patent [19]

Weder et al.

[11] Patent Number: Des. 362,823

[45] Date of Patent: ** Oct. 3, 1995

[54] FLOWER POT COVER

[75] Inventors: Donald E. Weder; Joseph G. Straeter, both of Highland, Ill.

[73] Assignee: Highland Supply Corporation, Highland, Ill.

[*] Notice: The portion of the term of this patent subsequent to Nov. 5, 2005 has been disclaimed.

[**] Term: 14 Years

[21] Appl. No.: 808,360

[22] Filed: Dec. 16, 1991

Related U.S. Application Data

[63] Continuation-in-part of Ser. No. 710,272, Jun. 4, 1991, abandoned, which is a continuation-in-part of Ser. No. 617,454, Nov. 21, 1990, abandoned, and Ser. No. 411,249, Sep. 22, 1989, and Ser. No. 411,247, Sep. 22, 1989, and Ser. No. 411,245, Sep. 22, 1989.

[57] CLAIM

The ornamental design for a flower pot cover, as shown and described.

DESCRIPTION

FIG. 1 is a perspective view of our new flower pot cover design;

FIG. 2 is a reduced top plan view thereof;

FIG. 3 is a reduced side elevational view thereof;

FIG. 4 is a reduced bottom plan view thereof;

FIG. 5 is a reduced side elevational view of the front side thereof;

FIG. 6 is a top plan view of a second embodiment of our new design;

FIG. 7 is a top plan view of a third embodiment of our new design;

FIG. 8 is a reduced bottom plan view of FIG. 7;

FIG. 9 is a reduced side elevational view of the design of FIG. 1, the only difference being the angle of the skirt;

FIG. 10 is a reduced side elevational view of the design of FIG. 1, the only difference being the angle of the skirt;

FIG. 11 is a reduced side elevational view of the design of FIG. 6;

FIG. 12 is a reduced side elevational view of the design of FIG. 6, the only difference being the angle of the skirt;

FIG. 13 is a reduced side elevational view of the design of FIG. 6, the only difference being the angle of the skirt;

FIG. 14 is a reduced side elevational view of the design of FIG. 7;

FIG. 15 is a reduced side elevational view of the design of FIG. 7, the only difference being the angle of the skirt; and, FIG. 16 is a reduced side elevational view of the design of FIG. 7, the only difference being the angle of the skirt.

The flower pot cover has no substantial thickness.

The characteristic feature of the design resides in the specific pleating arrangement comprised of the parallel disposition of the exterior folds in combination with the interior V-shaped folds all as best shown in FIG. 1.

1 Claim, 4 Drawing Sheets
